(57) **CLAIM**

The ornamental design for a monitor prop, as shown and described.

DESCRIPTION

FIG. 1 is a front perspective view of a monitor prop showing my new design;

FIG. 2 is a front elevation view thereof;

FIG. 3 is a rear elevation view thereof;

FIG. 4 is a left side elevation view thereof, the right side view being a mirror image of that shown;

FIG. 5 is a top plan view thereof;

FIG. 6 is a bottom plan view thereof;

FIG. 7 is a perspective view thereof with the door in an open position; and,

FIG. 8 is a front perspective view thereof showing a monitor on its upper surface, the monitor not being part of the claimed design.
